CLAIM

The ornamental design for a wine bottle expansion chamber, as shown and described.

DESCRIPTION

FIG. 1 is a perspective view of a wine bottle expansion chamber embodying our new design;

FIG. 2 is another perspective view of the structure of FIG. 1 from a different perspective view in relation to FIG. 1; FIG. 3 is a front elevation view of the structure of FIG. 1; FIG. 4 is a rear elevation view of the structure of FIG. 1; FIG. 5 is a right elevation view of the structure of FIG. 1; FIG. 6 is a left elevation view of the structure of FIG. 1; FIG. 7 is a top plan view of the structure of FIG. 1; and, FIG. 8 is a bottom plan view of the structure of FIG. 1. In the drawings, the broken lines show portions of a wine bottle expansion chamber that form no part of the claim.

1 Claim, 4 Drawing Sheets
